G. BECKER.

FOLDING RECEPTACLE.

APPLICATION FILED JAN. 22, 1916. RENEWED DEC. 26, 1918.

1,295,674.

Patented Feb. 25, 1919.

UNITED STATES PATENT OFFICE.

GUSTAV BECKER, OF CHICAGO, ILLINOIS, ASSIGNOR TO PAUL M. FOWLER, OF CHICAGO, ILLINOIS.

FOLDING RECEPTACLE.

1,295,674.

Specification of Letters Patent.

Patented Feb. 25, 1919.

Application filed January 22, 1916, Serial No. 73,579. Renewed December 26, 1918. Serial No. 263,418.

To all whom it may concern:

Be it known that I, GUSTAV BECKER, a citizen of the United States, and a resident of the city of Chicago, county of Cook, and State of Illinois, have invented certain new and useful Improvements in Folding Receptacles, of which the following is a specification.

My invention relates to improvements in folding receptacles, and has for its object the production of a device of this character which will be of durable and economical construction and which may be readily and conveniently folded into compact form when not in use.

Other objects will appear hereinafter.

The invention consists in the combinations and arrangements of parts hereinafter described and claimed.

The invention will be best understood by reference to the accompanying drawing forming a part of this specification, and in which,

Figure 1 is a vertical transverse section of a shipping receptacle embodying the invention, showing the same in distended condition,

Fig. 2 is a view similar to Fig. 1, showing the receptacle in folded condition,

Fig. 3 is a section taken on line 3—3 of Fig. 2,

Fig. 4 is a side elevation of the receptacle as shown in Fig. 1,

Fig. 5 is an enlarged detail section illustrating the folding and sliding connection of the top of the receptacle with one of the lateral walls thereof, with the receptacle in distended form,

Fig. 6 is a view similar to Fig. 5 with the receptacle in folded or collapsed condition, and

Fig. 7 is a section taken on line 7—7 of Fig. 6.

The preferred form of construction, as illustrated in the drawing, comprises a rectangular bottom 10 at the ends of which are provided end walls 11 hingedly secured thereto as at 12. The side walls 13 of the receptacle are hingedly secured at 14 to supplemental side pieces 15 which arise from the longitudinal edges of the bottom. The arrangement is such, as will be seen, that in collapsing the receptacle, the end walls 11 are adapted to be folded down into position

against the upper side of bottom 10, whereupon the side walls 13 are adapted to be folded to superimposed positions above said end walls. The side pieces 15 serve to space the hinges of side walls 13 above the bottom 10 so as to afford clearance for end walls 11, as clearly shown in Fig. 2. When the receptacle is in distended condition, the end walls engage with channels 16 formed at the inner sides of side walls 13, at the ends of the latter, whereby said end walls 11 are securely held in vertical position.

The top wall 17 of the receptacle is provided at one edge with outwardly and downwardly extending connecting members or straps 18, the outer ends of said straps being formed with laterally extending projections or enlargements 19. Provided upon the outer side of one of side walls 13 are elongated channel members 20 which are rigidly secured in position in channels 16 formed for the reception thereof in said wall, as clearly shown in Fig. 7. The members 20 are formed at their outer sides with elongated slots 21 through which the outer ends of connecting members 18 are adapted to project, the lateral projections 19 of members 18 being adapted to slidably engage under the flanges constituted at the opposite sides of slots 21. The upper or outer ends of members 20 are closed as at 22, as clearly shown in Fig. 5, the opposite end of each of said members being closed by end walls 23, leaving open a passage between said wall portions 23 to accommodate the outer end of the corresponding connecting member 18, while at the same time obstruction is offered to the projections 19, as clearly shown in Figs. 2 and 6.

With the construction set forth, it will be seen that the connecting members 18 are slidably and swingingly connected with the members 20, thus resulting in a sliding and swinging connection of the top wall 17 with the corresponding lateral wall 13, so that in the collapsing of the receptacle the top wall is adapted to be swung and slid relatively to the corresponding lateral wall 13 in order to assume a position directly over the same, as clearly shown in Figs. 2 and 6. In unfolding the receptacle the reverse operation is of course resorted to. At the under side of the cover 17, adjacent the ends of the latter, are provided grooves or channels 16' for the re-

ception of the upper edges of end walls 11, whereby the latter are securely held in operative position.

Provided upon the top wall 17 at the free edge thereof is a hasp 24 adapted to engage with a loop 25 provided upon the corresponding side wall 13, whereby the former may be locked in closed position, and hence the receptacle in distended condition.

When the receptacle is in collapsed or folded condition, the hasp 24 is adapted to engage with a loop 26 provided upon one of the supplemental side pieces 15, as clearly shown in Fig. 2, whereby the receptacle is locked in this condition.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Copies of this patent may be obtained for five cents each, by addressing the "Commissioner of Patents, Washington, D. C."

Having described my invention what I claim as new and desire to secure by Letters Patent is:

A folding receptacle comprising a bottom; a side member hinged to said bottom and adapted to be folded to position over said bottom; a top; and a swinging and sliding connection between said top and said side member comprising a connecting member secured to the upper side of said top and projecting outwardly and downwardly therefrom around and outwardly of one edge of said top, said connecting member having an enlarged outer end, said side member having a slot with which said enlarged outer end of said connecting member swingingly and slidably engages, substantially as described.

In testimony whereof I have signed my name to this specification in the presence of two subscribing witnesses.

GUSTAV BECKER.

Witnesses:

JOSHUA R. H. POTTS,
CORA F. SCHIEBER.
